UNITED STATES PATENT OFFICE

94,954

DESIGN FOR A TEXTILE FABRIC

Curt Erwin Forstmann, Montclair, N. J.

Application January 5, 1935, Serial No. 54,737

Term of patent 14 years

To all whom it may concern:

Be it known that I, Curt Erwin Forstmann, a citizen of the United States, residing at Montclair, in the county of Essex and State of New Jersey, have invented a new, original, and ornamental Design for a Textile Fabric, of which the following is a specification, reference being had to the accompanying drawing, forming part thereof.

In the drawing, the sole figure of which is a plan view of a piece of the textile fabric embodying the design of the present invention, the cloth depicted is of a single color.

The design comprises parallel series of irregular prominences extending across the surface of the fabric in a grapevine-like tracery, touching at irregular intervals to define irregular oval figures, the surfaces of said figures being characterized by diagonal shots or crinkles of irregular length.

I claim:

The ornamental design for a textile fabric, as shown and described.

CURT ERWIN FORSTMANN.
